(57) **CLAIM**

The ornamental Design for a tire tread, as shown and described.

DESCRIPTION

FIG. 1 is a perspective view of a tire tread showing our new design, it being understood that the pattern repeats uniformly throughout the circumference of the tread;

FIG. 2 is a front elevational view thereof;

FIG. 3 is a side elevational view thereof;

FIG. 4 is a side elevational view of the opposite side from that shown in FIG. 3 thereto; and,

FIG. 5 is an enlarged fragmentary perspective view.

In the drawings, the broken lines defining the inner bead of the sidewall are for illustrative purposes only and form no part of the claimed design.
